UNITED STATES PATENT OFFICE.

JOHN A. PETRI, OF BROOKLYN, ASSIGNOR TO KOCH SONS & COMPANY,
OF NEW YORK, N. Y.

DESIGN FOR A BOOK OR ALBUM.

SPECIFICATION forming part of Design No. 19,529, dated December 24, 1889.

Application filed September 12, 1889. Serial No. 323,775. Term of patent 7 years.

To all whom it may concern:

Be it known that I, JOHN A. PETRI, a citizen of the United States, residing in Brooklyn, in the county of Kings and State of New York, have invented and produced a new and original Design for a Book or Album, of which the following is a specification, reference being had to the accompanying drawings, forming part thereof, in which—

10 Figure 1 represents two album-leaves as laid out flat, and Fig. 2 is a section of the same.

The leading feature of this design consists of a book or album the outline or configuration of the leaves of which is that of an irregular pentagon.

15 The top and bottom l m of the leaf are at right angles, or nearly so, to the back n , and the lines p and q of the front edge form an an-

gle 8. Usually the edges p q are of different length to harmonize in appearance with the ornamental configuration of the picture-opening t ; but the present design is not limited in this particular, as in some albums or books there are no openings, and the corners may be clipped or rounded without changing the design.

What I claim is—

In a design for a book, the design of the leaves, substantially as herein shown and described.

Signed by me this 9th day of September, 1889.

JOHN A. PETRI.
